APPARATUS FOR REDUCING CRUDE PETROLEUM.

1,274,405.

Specification of Letters Patent.

Patented Aug. 6, 1918.

Application filed September 25, 1916. Serial No. 121,933.

To all whom it may concern:

Be it known that I, CHAUNCEY B. FORWARD, citizen of the United States, residing at Urbana, in the county of Champaign and State of Ohio, have invented certain new and useful Improvements in an Apparatus for Reducing Crude Petroleum, of which the following is a specification.

This invention pertains to an apparatus for reducing crude petroleum and its residuums to a light volatile oil suitable for use in internal combustion engines or for any other purpose for which such oil can be used, and the invention consists in an apparatus embodying the means shown and described in my Letters Patent of the United States bearing No. 1,202,823, of October 31, 1916.

In the accompanying drawings, Figure 1 is a longitudinal elevation of the complete apparatus, partially sectioned or broken away here and there, and Fig. 2 is an enlarged sectional detail of portions of two separators and the means operatively connecting the same. Fig. 3 is a sectional elevation of a modification of the connections between separators.

As thus shown in both my former application, and in the present one, and especially in the form of the invention seen in Figs. 1 and 2, the numeral 2 represents a suitable steam boiler having a steam delivery pipe 3 which leads to a steam superheater coil 4 arranged, in this instance, within the boiler casing and from which superheated steam is delivered under high pressures through a main pipe 5 and a series of branch pipes 5' which discharge into the atomizer 6, located respectively at the front ends of the several successive separators 7, 8 and 9.

It will be understood that while I prefer to use steam in connection with this apparatus, I might employ air with suitable means for heating and delivering the same at the desired working temperatures and pressures through said pipes 5 and 5' and the injectors shown. At present, however, I employ steam, and the oil is taken from a supply tank 11 and forced by the pump 12 under the requisite pressure into the first or primary separator chamber through the pipe 13 which is connected with the atomizer 6 of said separator, and a steam heater 14 of jacket form is connected with the superheated steam supply for the system and surrounds a portion of the said oil delivery pipe

13 to heat the oil to a correspondingly high temperature before it passes to the atomizer. This also helps to maintain the required temperature in separator 7, as without the pre-heating of the oil the temperature would be materially reduced therein.

In my experience with the original apparatus referred to above, and incorporated herein, I found that notwithstanding the unusually large percentage of light commercial oil yielded by the apparatus as a whole, there was still a valuable percentage of such oil to be obtained from the residuum which it was profitable to save. Hence the present invention involves the original apparatus and certain improvements thereon which have to do especially with the residual products of the process. For example, in the said original apparatus there was an appreciable lowering of the pressure from separator to separator, but it has been found preferable to increase the pressure as well as the temperature in each succeeding separator in order to more successfully break up the combination of molecules in the residuum and so that it will yield an additional percentage of the volatile oil. Therefore I conceived the idea of suitable steam injecting mechanism in that connection, whereby the residuum is effectually broken up in each transit from separator to separator and the separating conditions are materially improved.

To these ends, I employ a series of separators 7, 8 and 9, or two or more adapted each to receive the residuum from the one next preceding by a suitable pipe connection 15 opening practically into the bottom of the preceding separator and discharging into a steam injector *a*, of any approved pattern as shown in Fig. 2, and a volume of superheated steam is conveyed to said injector by a pipe *b* directly from the steam pipe 5 above under suitable valve control. Discharge from the injector is by pipe extension *b'* into atomizer 6. A check valve *c* prevents possible backflow through the pipe *b'* to the injector, and there is also a check valve *c'* in the steam pipe 5' next beneath the control valve *d* to prevent back flow from the separator.

As the pressure in the superheated steam supply is kept above that maintained in the separators I am enabled by these means to deliver the residuum flowing from one separator to another with such increase of tem-

perature and pressure as compared with the possibilities of the delivering separator that the breaking up of the combination of molecules in the residuum is materially enhanced 5 and the aggregate volume of volatile oil increased accordingly. The increased temperature in each successive separator is obtained by an increased volume of superheated steam to each in turn through the means just described.

It will be noticed, too, that this is accomplished at no added cost to the system after the apparatus has been installed, and there is no additional labor, or other expense, and the 15 operation is automatic and self-contained from first to last.

Each separator in the series has a separate vapor discharge connection 16 at its top and a clarifier 17 next to said connection discharging into pipe 19 through a pressure regulating valve 18, whence the delivery is to the condenser 20. Separate receptacles 21 and 22 may be used to receive the volatile oil from condenser 20 and the residual discharge 25 from the pipe 23 of the last separator 9, and a common blow-off pipe connection 24 is also provided for all of the separators, so that one or more may be operated or cleaned out at will. The several steam and oil pipes and 30 connections are provided with suitable valves wherever needed to control or shut off the flow of steam and oil for and during operations.

In practising the process, the crude oil is 35 forced by pump 12 into the first or primary separator 7 together with superheated steam, the oil being also preferably heated initially by heater 14. The superheated steam is delivered under sufficient pressure to atomize 40 the oil effectually as it enters the separator, and such introduction of the atomized oil proceeds continuously while the temperature in separator 7 is maintained at about 400 degrees F. or higher by the steam supply. 45 The pressure in each separator is regulated by the pressure-regulating valve 18 above the clarifier 17, which opens only to permit the vapor to escape when a predetermined pressure is exceeded and because the outflow of the residue through pipe 15 to the 50 next separator is restricted and controlled by a valve 15'.

Obviously, vapor pressure established and maintained in the primary separator 7 55 through pipe 4' from the superheater 4 occasions pressure in the vapor discharge by channel 16, the separator 17 and the vapor carrying pipe 19 and also to the residuum discharge through pipe 15, and this pressure 60 contributes to force the residuum into the next succeeding separator and on to the next, but with lowering pressures successively if no auxiliary pressure be employed. Pipe 5' to each separator from the distributing pipe

5 contributes a greater or less proportion to 65 the pressure and heat, but greatly improved results are obtained by the use of an injector α or its equivalent.

In Fig. 3, I show a modification of the portion of the invention embodying injector α and for which I substitute an injecting pipe 25 which leads from the superheated steam supply pipe 5 and projects through a four-way cross, or its equivalent, 24, set into the down pipe 15 from the bottom of the 75 separator and has its discharge into the next separator chamber by pipe 26 connecting with the said part 24. The said injector pipe 25 extends some distance into the larger end of pipe 26 and is designed to facilitate the 80 atomization of the residuum and to increase temperature and pressure substantially as occurs in Fig. 2, with injector α . Pipe 26 has an atomizer 27 at its extremity in the end of the separator, and a hand controlled 85 valve 28 therein serves to govern inflow and a check valve 29 prevents back pressure from the next separator.

Obviously, predetermined and even pressure and temperature in the separating 90 chambers would be impossible if there were not suitable means to control the outlets therefrom, and such control is preferably by valves which are set by hand as the conditions require.

The separating chambers herein are preferably arranged tandem, as shown, with the residual products from a given chamber flowing under pressure from the bottom thereof to the end of the next chamber and 100 where the oil or residuum is atomized openly into the body of the chamber in the presence of the uniformly maintained pressure therein, which may be seventy-five pounds to the square inch, more or less. Hence, also, the 105 importance of artificial or mechanical pressure behind the oil, as by pump 12.

The separating chambers being individual and exposed to the open air and without external heat, I find it advantageous to cover them thoroughly with asbestos or the like to prevent undue radiation. It is my aim to have substantially the same separating conditions in all the chambers, and since both heat and pressure which come over from a 115 given chamber are more or less diminished in transit the difference can be more than made up by superheated steam forced in through pipes shown and described.

Attention is called in this connection to 120 my pending application, Ser. No. 29,997, filed May 24, 1915, in which a claim appears for an apparatus with a chamber having outlet passages for the vapors and the residuum respectively, means to atomize the oil 125 into the open interior of said chamber against a maximum pressure therein of at least sixty pounds to the square inch, and

means in said passages adapted to maintain said pressure and to prevent the escape of vapor through the passage for the residuum.

What I claim is:

- 5 An apparatus as described, comprising a series of separator chambers, means to force oil and superheated steam together into the first of said chambers and to maintain a predetermined vapor pressure therein, a passage
10 for vapor from the top of each chamber and
- a passage for the residuum from the bottom thereof arranged to discharge into the next succeeding chamber, means to add superheated vapor to said residuum in said passage and an atomizer for the residuum at the 15 discharge end of said passage.

Signed at Cleveland, in the county of Cuyahoga, and State of Ohio, this 7th day of September, 1916.

CHAUNCEY B. FORWARD.
